(Cl. D67—3)

To all whom it may concern:

Be it known that I, Donald E. Dailey, a citizen of the United States of America, residing at Old Petersburg Road, Center Township, in the county of Vanderburgh and State of Indiana, have invented a new, original, and ornamental Design for a Combination Refrigerator and Dispensing Bar, of which the following is a specification, reference being had to the accompanying drawing, forming part thereof.

The instant design of a refrigerator is a continuation-in-part of the design disclosed in my prior application Serial No. D. 17,345 filed November 9, 1951, now Patent No. D. 167,825, September 30, 1952, and relates back to said prior application for all common subject matter.

Fig. 1 is a perspective view of the combination refrigerator and bar embodying my new design and showing the dispensing bar formed by the open door and the interior of the refrigerator at the rear of the bar; and

Fig. 2 is a perspective view similar to Fig. 1 but more clearly disclosing the extent of the dispensing bar formed by the open door.

The characteristic feature of my instant design resides in the interior appearance as viewed when the door is open. The rear and side of the refrigerator not shown are substantially plain.

I claim:

The ornamental design for a combination refrigerator and dispensing bar, as shown and described.

DONALD E. DAILEY.
